DESIGN FOR A GAME BOARD

Thomas Thomsen, Chicago, Ill.

Application May 8, 1934, Serial No. 51,721

Term of patent 3½ years

To all whom it may concern:

Be it known that I, Thomas Thomsen, a citizen of the United States, residing at Chicago, in the county of Cook and State of Illinois, have invented a new, original, and ornamental Design for a Game Board, of which the following is a specification, reference being had to the accompanying drawing, forming part thereof, and in which:

Fig. 1 is a plan view of the game board; and
Fig. 2 is an end elevation.

I claim:

The ornamental design for a game board, as shown.

THOMAS THOMSEN.
